BLOOD COLLECTION APPARATUS

Edward Sohier Welch, Jr., Framingham, Mass., assignor, by mesne assignments, to Baxter Laboratories, Inc., Morton Grove, Ill., a corporation of Delaware

Filed Aug. 3, 1956, Ser. No. 602,006

25 Claims. (Cl. 128—276)

This invention relates to blood handling and more particularly to the controlled collection of blood in collapsible containers. The invention aims at controlling the blood collection for minimum discomfort to the donor and for no damage to the blood cells. The invention provides new and improved method and apparatus for applying reduced pressure or partial vacuum to and through the collapsible containers in the blood collection, and for controlling the partial vacuum for optimum rate and also uniformity of flow of the blood. The invention contemplates and provides additionally for mixing the blood with a preservative during collection; for detecting and measuring the volume of the collected blood; and for stopping the collection automatically upon the filling of the collapsible containers with desired, determined blood volumes. The invention will be better understood from a consideration of the following specification taken in conjunction with the accompanying drawings in which:

Fig. 1 is a front end view of the invention apparatus shown with a container installed in the chamber for blood collection;

Fig. 2 is a side view of the apparatus illustrating the agitation of the chamber;

Fig. 3 is a partly schematic view of the blood collection controlling apparatus of the invention, illustrating the relation and coupling of the chamber evacuating and agitating means;

Fig. 4 is a fragmentary, larger scale top plan of the apparatus showing the vacuum line valve, the tube clamp and the chamber door in the non-operative position;

Fig. 5 is a view like that of Fig. 4 but showing the similar elements in the operative position;

Fig. 6 is a vertical section, on a still larger scale, showing the passing of the container inlet tube through the chamber wall, and also the closing of the tube by the clamp as in Fig. 4;

Fig. 7 is a horizontal section, on a scale still further enlarged, taken through the container inlet tube, and illustrating the reception of the tube and also the leakage opening through the chamber wall; and

Fig. 8 is a schematic view of a modified form of the blood collection controlling apparatus of the invention.

In the collection of blood and more particularly human whole blood, it is desired first that the blood be collected at a uniform rate, affording minimal physiologic disturbance to the donor, and so as to preclude damage to the blood cells. It is desirable also to obtain and store the blood in determined or measured volumes. A further requirement is that the blood be agitated in the collection, as for mixing with previously introduced anti-coagulant solution, in minimum space, with minimum effort, and without injury to the blood components.

The collection of blood, as for storage or "banking," has generally been accomplished heretofore with rigid containers such as glass bottles. This collection of blood in glass bottles has proven difficult and disadvantageous. In many cases, the blood collecting bottle is vented to allow the escape of air from the bottle as the blood flows

2

in by donor venous pressure and gravity. This method has the disadvantage of not being a completely closed system and furthermore provides no way of increasing the rate of blood-flow.

It is common practice also to use a closed bottle that has been nearly completely evacuated initially. It is found, however, that introducing fresh whole blood into a nearly complete vacuum is damaging to the red cells.

10 In other cases, the required vacuum is established by arranging a vacuum system for opening and continuously evacuating through the bottle closure. But the hazard of contamination from the piercing of the bottle closure, and the inconvenience, otherwise, of the use of a vacuum system with glass bottles have made this method relatively unacceptable in practice.

The shaking or agitation of the rigid containers, for the required mixing of the blood with a preservative, has also proven difficult. More particularly, rotating or oscillating a reasonable size or heavy glass bottle consumes space, introduces mechanical problems, and, due to the inevitable air-blood interface, results in a cell-damaging sloshing or even a "water hammer" action between the blood and the bottle walls and between colliding portions 25 of the blood, all as well known to those skilled in the art.

While the desired detecting or measuring of the collected blood volume may be accomplished with these rigid glass containers by optical or weighing means, it 30 may not be conveniently carried out coincident with the aforementioned agitation. But this container shaking is continuously necessary to the adequate mixing of the blood with the anti-coagulant or the like preservative solution during collection. It follows that with these 35 glass or other rigid containers, determination of the volume necessitates the unwanted interruption of the agitation.

The more recently introduced collapsible containers, which are now also generally employed in blood banking practice, have been found better suited to and more 40 readily manipulated for desired control of the blood collection. With such collapsible containers, including the plastic bag herein shown by way of example, the reduced pressure or partial vacuum required or desired to 45 induce or increase the rate of flow of the blood from the donor's veins can be established without, and transmitted undiminished through, the flexible container walls. It will be apparent that a partial vacuum which can thus be established inside by a system wholly outside the 50 containers can be controlled also for desired uniformity of rate of collection. Moreover, and in view of the collapsibility and light weight of these plastic or the like containers, their agitation may be accomplished with much lighter devices, in smaller space, and without 55 deleterious effect on the blood, the air-blood interface being eliminated by the initial collapse of the containers.

Further, detecting or measuring the volume of the 60 collected blood may be carried out automatically and in conjunction with the continuous agitation of the collapsible containers. For it is found that the external dimensions of such containers are closely proportional to their contained volume, so that the expansion in filling of the containers provides a continuous indication of the amount of blood collected. Thus the collapsible containers here concerned permit a direct, accurate and 65 continuous indication of their contained volume. It will be apparent that the container expansion can be detected and measured non-interferently with the agitation of the containers during collection. More importantly, this continuous detection of blood volume by measuring container expansion can be employed also for automatically 70

stopping the flow of the blood, and optionally the container agitation, upon the completion of the blood collection.

My present invention provides a convenient, accurate and fast method and apparatus for controlling the collection of the blood in these collapsible containers. It affords more particularly improved method and apparatus employing and applying these several features and characteristics of the handling and use of such containers. My invention is distinguished also by the ease and simplicity of handling of the containers; by the directness and accuracy of the blood volume measuring, and compatibility of such measuring with the agitation of the blood in collection; and by the application of the blood volume measuring to the control and automatic stopping of the container filling and agitating. In the form here concerned, the invention apparatus provides a chamber adapted easily and simply to be loaded with a collapsible blood container, and which may be evacuated to induce the flow of the blood into the container, and also agitated for the required mixing of the incoming blood with the previously introduced preservative. The apparatus chamber will be seen further to be sufficiently confining of the containers to mount means adapted for engaging the container wall, upon its expansion in collection. Pursuant still further to the invention, such means is employed for controlling, ordering, and signalling the stoppage of the collection of the blood, and, optionally, the agitation of the container.

Referring now more particularly to the drawings, there is shown in Figs. 1 and 2 the housing or panel 10 such as may mount or support various of the apparatus components, and which may in turn rest on a larger or wider base or stand 11, as may be fitted with feet or the like 12. The housing or stand 10, 11 may be fashioned of metal or other material of a strength, weight and durability appropriate to the support and protection of the apparatus components, and it may mount the usual carrying handle and name plate or other identification means, not shown.

In accordance with the invention, there is supported from the housing 10 a plastic or other transparent light weight rigid chamber 20 for receiving and enclosing a blood container, and herein comprising the cylinder 21 closed at its one end 22 and fitted at its other with an access lid or door 23 which may be freely swung, as on the pivots or hinges 24, from the open or Figs. 1, 2 position through the Fig. 4 position to the fully closed position of Figs. 5 and 7. The container receiving chamber 20 is provided further with a tray or shelf 26 on which the blood container is placed and supported. The bag or pack herein illustrating the collapsible container is indicated at C, and will be seen to be of bladder-like construction, such as defined by a flexible sleeve flattened and sealed at its ends. It has sealed to or through one said end an integral inlet or donor tube T, such as fitted with a needle and applied to the arm of a donor D, Fig. 1, for collection of the blood. The container and inlet C will be understood to comprise a substantially integral closed, sealed, blood handling system of flexible, transparent, light weight, and durable construction, and which may be substantially free of air, as for elimination of air-blood interface. Further, it is fashioned of a plastic or other material susceptible of sterilization, and characterized also by hemorepellence. The container C may be fashioned for a contained fluid volume of say, 500 cc., and it may be supplied with a suitable quantity, in such instance 75 cc. of an anti-coagulant or preservative solution such as desired to be continuously mixed with the blood in its collection, all as conventional in the art.

The closed, sealed, hemorepellent blood collecting and storing system C, T will be understood to be installed in the apparatus with the container C rested on chamber shelf 26, initially in the flatwise position of Fig. 1, and with the donor tube T received through a round hole 27, Fig. 7, cut through cylinder 21 tangent to door 23. A slot 27a is also formed in the chamber cylinder, said

slot extending between and normal to said hole 27 and the cylinder open end, and proportioned to permit the ready insertion of the tube T into the annular, close fitting opening 27, and to provide also a small leakage path for passage or bleed of air into the chamber 20 when the door 23 is closed.

My novel blood collection controlling apparatus comprises further means for continuously agitating the cylinder 21, for the desired mixing of the blood with the preservative. The agitating means herein illustrating the invention is seen to comprise a reciprocating or oscillating motor 30 having a rotating arm or shaft 31 which may be joined to the chamber 20 by a surrounding strap or sleeve 32 having a clamp fastening 32a, Fig. 1. The motor 30, which may be of the vacuum operated type such as commonly employed for automotive windshield wipers, is provided with a manual on-off control switch or valve 33 and a manual speed control or throttling valve 34. The motor 30 will be understood to drive shaft 31 so as to oscillate or reciprocate the chamber 20 about a diametrical axis at or near the center of the chamber length, and through a small horizontally centered arc, as indicated by the solid and dotted line chamber positions, Fig. 2. The rate of this chamber oscillation is regulated by adjustment of throttling valve 34.

Further in accordance with the invention, means are provided for evacuating the cylinder 21 for and during the collection of the blood, and comprising a vacuum source or pump such as indicated at 40, Fig. 3, and which

30 may be coupled to and communicate with the chamber 20 through vacuum line 41, Figs. 1 and 3. The degree of vacuum applied through line 41 may be controlled or regulated by a regulating type valve 42 such as mounts a screw adjustment 42a. The vacuum system and line 35 40, 41 is seen to terminate and communicate with the chamber 20 at a nipple 43 entering or threaded through the cylinder 21 at a point centered above the collapsible bag or container C, Figs. 1, 2.

In accordance with the invention, the vacuum line 41 40 comprises further a series valve herein formed as a block 44 mounted on chamber 20 and having parallel passages 45a, 45b coupled to the hoses 41a, 41b which connect it with the vacuum valve 42 and port 43 respectively. The block passages 45a, 45b are seen as cross-connected by a passage 46 in which slides stem valve 47 having the annular peripheral recess 47a connecting the passages 45a, 45b in the open position, Fig. 5. The valve stem 47 is resiliently biased from its open or Fig. 5 position by coil or the like spring means 48 confined in slide passage 45b. The resilient biasing means 48 urges the slide 47 toward the seated position of Fig. 4, wherein it valves or closes, by the shift of the peripheral recess 47a out of alignment and communication with the passages 45a, 45b, the vacuum passage 41. The release of the energy stored in spring 48, to seat valve 47 and close line 41, is related to and more particularly follows automatically upon completion of the container filling, as hereinafter explained.

Means are provided by the invention for automatically 60 detecting and measuring the presence of a desired or determined fluid volume in the container C. As heretofore pointed out, under certain conditions the external dimensions of the collapsible container are closely proportioned to its contained volume, and so that when the container is on a flat surface the elevation of its upper wall above said surface, and for any volume, may be accurately predicted. Accordingly the container upper wall may be employed for operating a continuous volume indicator, or, as herein, it may be used for actuating a control or signal device when the contained volume has risen to a predetermined value. In the present embodiment, the invention apparatus is seen to regulate, measure, or signal the filling of the container C to the desired volume simply by adjustment of the vacuum port or threaded nipple 43 to the appropriate height above the shelf 26. The

elevation of the container upper wall to the predicted height is then detected by its engagement with said nipple 43. This engagement of the smooth plastic surface of the container C against the polished end of nipple 43 will be understood to occlude the port and seal off the chamber 20 from line 41. It will be apparent that the partial vacuum established in chamber 20 by pump 40 will then be dissipated by the bleed through passage 27a.

Further in accordance with the invention, this measuring or detecting of the desired container blood volume by occlusion of the nipple 43 is employed to close and seal the container inlet or donor tube T against further blood flow automatically, and without interference with the agitation of the container. Referring now more particularly to Figs. 4 and 5, there is provided on cylinder 21 and overlying round hole 27 a pinch clamp comprising the block 50 pivoted as at 51 for shifting of its bearing or clamp face 52 toward and away from a generally parallel extension or leg 49 of fixed valve block 44. The block 50 is seen further to be engaged by and between, and more particularly to be controlled or engaged and shifted by a pin 25 on chamber door 23, and oppositely by the valve slide 47. Thus closing of the door 23, as under the influence of container vacuum, urges and rotates clamp block 50 clockwise to the open position of Fig. 5. Seating of the valve 47, as by the thrust of spring 48, will drive the block 50 counterclockwise to the left, to the closed position of Fig. 4, in which the clamp is seen to close on and seal the container inlet tube T. Spring 48 is selected or conditioned for a thrust less than that oppositely exerted on block 50 by the pin 25, when the normal partial vacuum obtains in chamber 20 and generates the intended negative or closing pressure at door 23, so that clamp 50 is normally urged and confined to the right or open position of Fig. 5.

In the operation of the invention apparatus vacuum pump 40 may be started with motor valve 33 closed, so as to drive arm 31 to one limit of its excursion and thus elevate the entrance end of chamber 20 for more convenient access through door 23. The closed collapsible, blood storing system C, T is then installed by laying the container C on shelf 26, holding open clamp 49, 50 for insertion of tube T into the cylinder opening 27, and then releasing the block 50 to clamp the tube T. With the container C thus closed the sterile sealed blood collecting assembly may be opened, as by removal of the usual protective sheath from the tube seated collection needle. Phlebotomy is then performed, with application of the needle to the arm of the donor D, Fig. 1. The collection of the blood and filling of the container C is commenced by closing the door 23, which again opens inlet clamp 49, 50, and also shifts valve 47 to open vacuum line 41. The evacuation of the chamber 20 is thus commenced automatically upon and simultaneously with the initiating of the flow of the blood. As earlier noted, the pressure difference across door 23 resulting from the evacuating of chamber 20 is such as to hold the door closed against the force of spring 48. The chamber oscillating motor 30 may now be started up, by manipulating valve 33, to oscillate chamber 20 for the desired agitation of the container C, and continuous mixing of the incoming blood with the previously introduced anti-coagulant.

The rate of blood flow into the container, in part physiologically determined, is controlled in further part by adjustment of vacuum regulator valve 42. Thus during the collection the cylinder 21 is continuously pumped and maintained at a level of vacuum as determined by the setting of the screw 42a. It will be understood that the rate of pumping necessary to maintain the desired vacuum is determined by the size of leakage or bleed path or slot 27a, Fig. 7.

As earlier noted, the filling of the container C to the desired blood volume is signalled by the rising or elevating of its upper wall to sealing or port closing engagement with nipple 43, the height of which is set and calibrated

prior to collection. The evacuation of chamber 20 is thus halted, with the result that, with the continuing air influx through bleed 27a, the chamber pressure is caused to rise rapidly to atmospheric. This, of course, equalizes the pressure across the door 23. The energy stored in spring 48 is thus again released to drive valve 47 to open the door and close clamp 49, 50 and tube T against further blood flow into the container C. The vacuum motor 40 may then be turned off manually, the tube T clamped by other and conventional means, and the container C removed from the evacuating chamber 20, which is then and thereby ready for another container filling cycle.

In the modification shown in Fig. 8, which will be understood to duplicate the Fig. 3 form in all other respects, the blood collecting apparatus is provided in addition with means for automatically starting and stopping the oscillation of evacuating chamber 20. More particularly, a flexible hose 60 is arranged for communication at its one end with the chamber 20 and mounts at its other 15 end a flexible bellows 61. The hose and bellows 60, 61, and said chamber 20 will be understood to be constructed and arranged such that the pressure within each is always, for practical purposes at least, identical. The bellows 61 is supported at its one end and coupled to and for 20 shift of motor valve switch 33 at and by its other and free end.

Thus in the operation of the apparatus of Fig. 8 the evacuation of chamber 20 which initiates the blood flow serves also to collapse bellows 61 and hence automatically 25 to shift valve 33 to start oscillating the motor 30. Similarly, at the end of collection the return of the chamber to atmospheric pressure reverses this processing and more particularly expands bellows 61 automatically to reposition valve 33 and stop motor 30. It will be readily appreciated that this automatic agitation control serves as an additional visual indication of the completion of the blood collection.

In the collection of the blood the flow through donor tube T with its attached needle may sometimes be impeded, as by occasional blood clots. In accordance with 40 the invention, the donor tube may be cleared by overriding the regulated vacuum and subjecting the container C to full pump vacuum. Thus in both the Figs. 3 and 8 embodiments the vacuum line 41 may comprise also a 45 passage paralleling or by-passing regulating valve 42, and normally closed, as by a spring valve 62. At the discretion of the operator, line 41 may be opened and chamber 20 voided to the full vacuum of pump 40 merely by finger pressure against valve 62.

It will be understood that my invention is not limited to the particular embodiments thereof illustrated and described herein, and I set forth its scope in my following claims:

1. Apparatus for controlling the collection of blood 55 in a collapsible container having an inlet comprising a chamber for enclosing the container, means for agitating said chamber, means for evacuating the chamber, means operable during agitating for detecting the container blood volume, and means governed by said detecting means for closing the container inlet.

2. Apparatus for controlling the collection of blood in a collapsible container comprising a chamber for enclosing the container, means for agitating said chamber, means for evacuating the chamber, and means for detecting and acting upon the detection of a predetermined container volume to stop the collection at that predetermined container volume.

3. Apparatus for controlling the collection of blood in a collapsible container comprising a chamber for enclosing the container, means for evacuating said chamber, means for automatically regulating said evacuating means to maintain a predetermined level of vacuum in the chamber, means for agitating the chamber, and means 70 controlling said agitating means to start and stop auto-

matically upon the starting and stopping of the evacuating means.

4. Apparatus for controlling the collection of blood in a collapsible container having an inlet comprising a chamber for enclosing the container, means for evacuating the chamber, means for signalling the collection of a predetermined blood volume, and means responsive to the operation of said signalling means for occluding said evacuating means and said container inlet.

5. Apparatus for controlling the collection of blood in a collapsible container having an inlet comprising a chamber for enclosing the container, means for agitating said chamber, means within said chamber and operable during said agitating for detecting the container blood volume, and means governed by said detecting means for closing the container inlet upon the collection of the detected blood volume.

6. Apparatus for controlling the collection of blood in a collapsible container comprising a chamber for enclosing and supporting the container, means for agitating said chamber, and means operable during said agitating for detecting the container expansion to a predetermined height and thereby the blood collection to a predetermined volume.

7. Apparatus for controlling the collection of blood in a collapsible container comprising a chamber for enclosing the container, means for agitating the chamber, and adjustable means within said chamber for detecting any predetermined container volume, said means operable during said agitating to stop and thereby signal the collection of the blood in any such predetermined volume.

8. Apparatus for controlling the collection of blood in a collapsible container comprising a chamber for enclosing the container, means for evacuating the chamber, chamber carried means for measuring and signalling the collection in said container of a predetermined blood volume, and means for occluding said evacuating means, said occluding means operable responsive to said signalling by said measuring means.

9. Apparatus for controlling the collection of blood in a collapsible container comprising a chamber for enclosing the container, evacuating means for said chamber, said means automatically valved by filling of said container to a determined blood volume, and means actuated automatically by the valving of said means for closing the container inlet.

10. Apparatus for controlling the collection of blood in a collapsible container comprising a chamber for enclosing the container, chamber evacuating means ported within said chamber and for valving by determined expansion of said container, and clamp means for engaging the container inlet and operable automatically upon and by said valving to close said inlet.

11. Apparatus for controlling the collection of blood in a collapsible container comprising a chamber for enclosing the container, a bleed opening to said chamber, means for establishing a regulated vacuum in the chamber, said means rendered inoperative by determined expansion of said container, a door for sealing said chamber, said door held closed by the operation of said vacuum establishing means, a clamp for closing the container inlet, said clamp engaged and held open by the closing of said door, and means biasing said clamp oppositely of said door and operable to close said clamp and open said door automatically upon the rendering inoperative of said vacuum establishing means.

12. Apparatus for controlling the collection of blood in a collapsible container comprising a chamber for enclosing the container, evacuating means for said chamber, means for valving said evacuating means upon the filling of said container to determined volume, a vacuum-closed door on said chamber, means for closing the container inlet, said means disengaged by and during the closing of said door, and means for actuating said inlet

closing means automatically upon said valving of said evacuating means.

13. Apparatus for controlling the collection of blood in a collapsible container comprising a chamber for enclosing the container, a vacuum-closed door on the chamber, evacuating means including a vacuum line opening into said chamber and sealed by determined expansion of said container, a clamp for the container inlet, said clamp held open by said door, a valve in said vacuum line, said valve held open by said clamp, spring means for closing said valve and clamp and opening said door, and a container bleed whereby said spring means is operable to close said valve and clamp upon the sealing of said evacuating means.

14. Apparatus for controlling the collection of blood in a collapsible container having an inlet comprising a chamber for enclosing the container, means for developing a controlled degree of vacuum in the chamber, means affording an air bleed to the chamber, means for detecting the collection of a predetermined blood volume and for thereupon stopping said vacuum developing means, a clamp engaging and conditioned to close the container inlet, and means for holding open said clamp subject to said controlled degree of vacuum, said holding open means permitting said clamp to close upon the dissipation of said vacuum by said bleed means following the stopping of said developing means.

15. Apparatus for controlling the collection of blood in a collapsible container comprising a chamber for enclosing the container, a chamber oscillating motor, a control for said motor, means for evacuating said chamber, and a variable volume member communicating with said chamber and having a movable wall positioning said control.

16. Apparatus for controlling the collection of blood in a collapsible container having an inlet comprising a chamber for enclosing the container, means for maintaining a vacuum in said chamber, means operable upon the collection of a predetermined blood volume to dissipate said chamber vacuum, and means responsive to said vacuum dissipation for closing the container inlet.

17. Apparatus for controlling the collection of blood in a collapsible container comprising a chamber for enclosing the container, means including a fluid line for evacuating said chamber, a clamp for closing the inlet to said chamber, a valve in said line and engaging said clamp, means for seating said valve and closing said clamp, and vacuum operated means opposing and overcoming said seating and closing means during said collection.

18. Apparatus for controlling the collection of blood in a collapsible container comprising a chamber for enclosing the container, means for evacuating the chamber, means automatically regulating said evacuating means for a determined level of vacuum in the chamber, and means associated with said chamber and operable during said evacuating for measuring the blood volume collected in said container.

19. Apparatus for controlling the collection of blood in a collapsible container comprising a chamber for enclosing the container, means for developing a vacuum in the chamber, means automatically regulating said developing means for a determined lower level of vacuum in the chamber, and means for by-passing said regulating means to subject said chamber to the full vacuum of said developing means.

20. For controlling the collection of blood in a collapsible container, a chamber for enclosing the container, a door on said chamber, a vacuum line to said chamber, and means operative upon the opening and closing of said door to close and open said line.

21. For controlling the collection of blood in a collapsible container having an inlet, a chamber for enclosing the container, a door on said chamber, a vacuum line to said chamber, and means operative upon the opening

and closing of said door to close and open said line and said inlet.

22. For controlling the collection of blood in a collapsible container, a chamber for enclosing the container, a door on said chamber, means for evacuating the chamber, means for agitating the chamber, and means operative upon the closing and opening of said door to start and stop said evacuating and agitating means.

23. For controlling the collection of blood in a collapsible container having an inlet, a chamber for enclosing the container, means for closing and opening the container inlet, means for evacuating the chamber, means for agitating the chamber, and means for starting and stopping said evacuating and agitating means dependent upon the closing and opening of said inlet.

24. Apparatus for controlling the collection of blood in a collapsible container having an inlet comprising a chamber, means in the chamber for detecting the collected blood, and means controlled by said detecting means for closing said inlet upon the collection of a predetermined blood volume.

25. Apparatus for controlling the collection of blood

in a collapsible container having an inlet comprising a chamber, means in the chamber for detecting the collected blood, means for evacuating the chamber, means for agitating the chamber, and means operable to close said inlet and stop said evacuating and agitating responsive to the detecting of a predetermined blood volume.
